**BLOWER UNIT FOR HYDROTHERAPY OR
SIMILAR USE**

Randolph J. Smith, 618 Elmwood St.,
Anaheim, Calif. 92805

Filed Mar. 25, 1966, Ser. No. 1,643

Term of patent 14 years

(Cl. D83—1)

FIG. 1.

FIG. 2.

FIG. 3.

FIG. 4.

FIG. 5.

FIG. 1 is a front elevational view of a blower unit for hydrotherapy or similar use showing my new design thereof;

FIG. 2 is a right end elevational view thereof, the left end elevational view thereof being symmetrically identical;

FIG. 3 is a rear elevational view thereof;

FIG. 4 is a top plan view thereof; and

FIG. 5 is a bottom plan view thereof.

I claim:

The ornamental design for a blower unit for hydrotherapy or similar use, substantially as shown.
